UNITED STATES PATENT OFFICE.

WILLIAM P. QUENTELL, OF NEW YORK, N. Y.

TYPE-WRITING MACHINE.

SPECIFICATION forming part of Letters Patent No. 624,864, dated May 9, 1899.

Application filed May 27, 1898. Serial No. 681,943. (No model.)

To all whom it may concern:

Be it known that I, WILLIAM P. QUENTELL, a citizen of the United States, residing at New York, in the county and State of New York, 5 have invented new and useful Improvements in Type-Writing Machines, of which the following is a specification.

This invention consists in the novel features of construction set forth in the following specification and claims and illustrated in the annexed drawings, in which—

Figure 1 is a plan view of the machine, partly broken away. Fig. 2 is a sectional side elevation on the line 22 of Fig. 1. Fig. 3 is a 15 sectional side elevation like Fig. 2, on a larger scale, and some parts broken. Fig. 4 is a plan view of the machine with the carriage and some other parts removed. Fig. 5 is a detail view of a hammer-detent. Fig. 6 is a rear 20 elevation of certain parts of the machine. Fig. 7 shows a blank for a type-segment section. Fig. 8 is a plan view of Fig. 6. Fig. 9 shows the body portion of a type-segment. Fig. 10 is a view like Fig. 9 with the 25 segment-hub added. Fig. 11 is a side elevation of Fig. 8. Fig. 12 is a detail view of a speeding arrangement serviceable in connection with the spacing-key.

The machine shown in the drawings is of 30 the kind employing a type segment or wheel. A hammer suitably actuated strikes or presses the sheet or paper against the required type on the wheel to produce a print or impression. The machine is shown with a base 1, 35 Figs. 1 and 2, and has a way or track 2, Figs. 1 and 3, for a paper-carriage 3. The feeding mechanism of the carriage, comprising a rack 4 and dog 5, is known and need not be described in detail.

40 The dog 5 has its rock-shaft or fulcrum at 6 and is moved or held to one position by arm 7 and spring 8, secured to a suitable part or fixed post or block 9, Figs. 3 and 4. The dog 5 is rocked against the tension of spring 8 by arm 10, connected or linked at 11 to arm 12, extending from rock-shaft 13, which latter has the laterally-extending arm 14.

45 The free end portion of arm 14, as indicated at 15, is bent or extended under or into 50 engagement with the cross-bar 16 of a bail, the lateral branches of which are shown at

17. The bail has its fulcrum or rock-shaft at 18.

At 20, Fig. 2, are shown the buttons or finger-pieces of the keys or key-levers 21, fulcrumed in a suitable bearing or strip 22, Fig. 55. 3. The keys extend across or engage the cross piece or bar 16 of bail 17, and the keys at opposite sides of the machine also extend, respectively, across the cross pieces 60 or bars 23 of levers 24, fulcrumed at 26. The levers 24 are shown at opposite sides of the machine. For convenience of description the levers 24 can be called "printing-levers." Each such printing-lever, as will presently 65 appear, gives the printing-stroke to hammer 27, Figs. 2, 3, and 4. Say that one-half of the keys 21, or the keys to one side of the machine, act on the cross-piece 23 of one of the levers 24, and the other set of keys actuate 70 the other levers 24. Then as a key of one set or another is actuated the respective printing-lever is moved.

It is noticed that in Fig. 1 the buttons 20 are shown; but for the sake of clearness the 75 key-levers 21 are omitted in Fig. 4.

The hammer 27 is shown on the pivot or with swinging support 28 and has a pin or oppositely-extending lugs 29. Each lever 24 has its rear arm extending positively or directly under or into engagement with pin 29. The depression of a front arm of lever 24 and consequent rise of its rear arm will give an upward or printing swing or stroke to the hammer. 80

85 The fulcrums 26 are each carried or mounted on a lever 30, Figs. 3 and 4, conveniently called "positioning-levers" since, as presently seen, they move the type-segment to bring the required type to printing position. 90 The positioning-levers are fulcrumed at 31, and each such lever is connected by a rigid or positive connection or stud 32 to a transmission-lever 33, fulcrumed at 35. Each lever by its upper arm 34 engages a shoulder 95 36 on shaft 37, and from the shoulder-piece 36 extends arm 38 39, engaging a spoke 40, Fig. 8, of the type-segment shown with hub portion 41 and rim portion 42.

Secured to shaft 37 is a stop-arm 43, and, as 100 seen in Fig. 3, the keys 21 when at rest are above the arm 43, so that the latter can swing

laterally under the keys. When a required key is depressed, it actuates a lever-arm 24, with fulcrum 26, and the consequent swing of the lever 30 swings shoulder-piece 36, with shaft 37, type-segment 42, and arm 43, until the latter is stopped by positive or direct contact with the depressed key. The type-segment has now carried or swung the required type to the printing-point and has come to a stop by the arrest of arm 43.

The lever 30 with fulcrum 26 have come to a stop with the type-segment, but the lever 24, continuing its swing, carries the hammer 27 along until it has made the print. 15 The actuated key being then released, the parts return to rest, as indicated in Figs. 1 and 2.

The paper-carriage can have a sheet stored or rolled in holder 44, Fig. 3, and fed out 20 between rollers 45 46, so as to lie back of plate 47, having a perforation 48, Fig. 6, at the printing-point. The ink-ribbon from spools 49 extends between the sheet and the type-segment, and when the hammer 27 forces 25 the paper through opening 48 against the required type an impression is secured.

The hammer 27 is generally so balanced as not to move ahead of time or until the type-segment has been actuated and arrested. In the 30 drawings, however, is shown a cam or detent to prevent racing or premature stroke by the hammer. Such cam is shown in detail at 50, Fig. 5, and at Fig. 3 the high part of the cam, or the part farthest from the rod 31, is shown 35 in contact with or in proximity to the hammer 27. The cam is connected to sleeve 51 on fulcrum or rod 31. A bail 52 53 is shown on the shaft 31 and its arms 52 carry a rod 54. The bail is connected to sleeve 51 by the 40 piece 55, connected to such sleeve and to rod 54. A returning-spring 56 engages rod 54.

The lever-arms 25, which engage hammer 27, are step-shaped or formed to engage the cam or its rod 54, so as to actuate the hammer and cam. As a lever-arm 25 raises the 45 cam and hammer, the cam or its high part is held or moved in advance of or clear of the hammer, and said cam being located in the path of the hammer in advance of the latter 50 a premature jump or stroke or excessive speed of the hammer is prevented. The cam is mounted clear of the hammer and is capable of moving out of contact with the latter and is so cut away or shaped that when the cam has been raised a certain distance the low or 55 cut-away portion of the cam permits the hammer to fly forward of its own momentum to print. The hammer is suitably cut away or slotted, as seen at 87, Figs. 3 and 4, so that 60 as soon as the cam 50 swings up it will clear or free the hammer by coming over the slot 87. Should the hammer acquire excessive speed or jump ahead or away from the lever 25, it will be checked by the cam until the latter has moved sufficiently to clear the way 65 for the hammer. The return-spring 56 can be made to return the hammer and bail, or

these parts might be made of such weight and so arranged or overbalanced as to return without the aid of a spring. 70

The type-segment is adapted to be made very light and at the same time sufficiently strong or rigid to answer its purpose. As seen in Figs. 9 and 10, the segment consists of an upper and a lower section provided with 75 lugs 57, made to engage one another or soldered or secured together for connecting the sections. The holders 58 are adapted for riveting or securing the type-strip or type in place along the segment-rim 42. The lugs 80 57 are shown at the outer spokes of the type-segment. Each segment-section being formed of a suitable blank, Fig. 7, of sheet or thin metal or stock and being corrugated or bent or flanged along the dotted lines shown in such 85 Fig. 7, such sections will be stiffened and will bring the lugs 57 to engagement with one another. The segment-sections being secured together at suitable distance or space apart, can receive the type-strip therebetween. A 90 sleeve or hub 59, Fig. 10, secured to the hub portions 41 of the two sections, is adapted to fit or be secured to shaft 37.

The holders 58 are shown in Fig. 7 as perforated, and when these holders are bent perpendicular or toward one another, as seen in 95 Fig. 10, screws or rivets passed through such perforations can be made to engage or hold a type-strip placed against the holder or lugs 58. 100

The ribbon-spools 49 are made shiftable or mounted on the shiftable support or plate 60, Fig. 6, so that such spools can be alternately brought into and out of engagement each with its respective driving-pawl 61 and retaining-pawl 62. One head of each spool being suitably notched, the pawls can engage the spool for driving and preventing retrograde rotation of the latter. The spool-actuating pawls 61 are mounted on rock-shaft 63, 110 having arm 64, Fig. 11, connected by link 65 with arm 12, Fig. 6, extending from rock-shaft 13.

The rock-shaft 13, actuated by the keys, as noted, actuates both the pawl-shaft 63 and 115 the dog-shaft 6 or is common to driving mechanism of the spool and carriage. The retaining-pawls 62 are mounted on suitable pivots or bearings and each held by a spring toward its respective spool. A stop 66 can be 120 arranged to prevent each stop-pawl 62 swinging too far or out of place when its spool is shifted clear of the pawl. The rock-shaft 63 swings the driving-pawl 61, so as to give a step-by-step rotation to one or another of the 125 spools to wind the ribbon back and forth. The shaft 63 and pawls 61 and 62, it is noted, are not shiftable.

The plate 60 has a shoulder 67, Fig. 8, and as the plate is shifted it is locked against accidental movement by spring 68 or the shouldered end of said spring engaging one side or another of shoulder 67. 130

The type-segment when provided with dif-

ferent rows of type is made to be shifted by the case or shift-levers 69, Fig. 1. Two such levers are shown, the segment being supposed to have three rows of type and the top row being normally in action or printing when the levers 69 are released. A fulcrum-block 71, Fig. 8, supports the screws or fulcrums 72 for the shift-levers fulcrumed to sides or lateral faces of the block. On top of the block 71 or between the shift-levers is a fulcrum 73 for a lever, having arms 74 75, the free ends of which are suitably inclined or cam-shaped, so that when a shift-lever is depressed and a lever-arm 74 or 75 is swung over the depressed shift-key the latter is locked to hold the type for printing with the required case until the lock 74 75 is released. As seen in Fig. 8, the lock-lever can be set so that both arms 74 and 75 are out of action.

As seen in Fig. 11, a block or base-plate 76 is differentially slotted at 77 and 78. Each shift-key 69 has its arms 70 entering into or limited in play by its respective slot. When the shift-key stopped in slot 77 is actuated, the middle case of type will print, while the key in longer slot 78 when swung to its full extent will bring the lowest case of type into action.

On the plate 76 normally rests plunger 79, adapted to be shifted by the keys 69, and an arm on the plunger is made to engage the segment or its hub 59 to shift such segment along shaft 37. This arm, as seen in Fig. 6, is composed of two jointed sections 80 and 81, the section 81 being normally in position or held by a spring to engage the segment and being adapted to swing or bend on section 80 to clear or release the segment—as, for example, when the latter is to be taken from the machine.

The writing-keys 21, being fulcrumed a certain distance back in the machine and extending forward, engage the spacing-bail 16 by resting directly or positively thereon, and each set of keys also engages or rests directly or positively on its respective printing-bail 23. These two bails, being suitably separated or spaced at the center, allow a spacing-key 83, fulcrumed at 18 and normally held raised by spring 19, Fig. 3, to play or descend without actuating the printing-bails; but such spacer can be made to engage or depress the spacing-bail 16. To effect speeding or enable the key 83 to space with comparatively slight movement, a lever 84, fulcrumed at 85 and made to contact with or support spacer 83 at 86, is placed intermediate the spacing-key 83 and the arm 14 and is made to engage the latter near the fulcrum or shaft 13—that is to say, at a greater or less distance from the free end 15 of said arm 14. The spacer 83 is centrally located or arranged to pass or clear through the central cut or break between the bails 23 without actuating such printing mechanism. The plunger 79, Fig. 11, when freed can be allowed to drop or descend by its weight; or its descent can be secured or aided by a suitably-applied spring.

What I claim as new, and desire to secure by Letters Patent, is—

1. A type-writing machine provided with a lever, and a hammer and detent made to rest directly on the lever when the parts are at rest so as to be simultaneously moved on the actuation of the lever substantially as described. 75

2. A type-writing machine provided with a lever, a detent, and a hammer composed of a rigid or unyielding arm or lever, said detent and hammer being made to rest on the lever when the parts are at rest substantially as described. 80

3. A type-writing machine provided with a hammer, a cam for the hammer, a sleeve to which the cam is connected, a bail connected to the sleeve, and a shaft for supporting the bail and sleeve substantially as described. 85

4. A type-writing machine provided with a hammer, a cam for the hammer, a bail connected to and made to move with the cam, a return-spring for the bail, and actuating 90 mechanism substantially as described for the hammer and bail.

5. A type-segment comprising sections provided with holders for the type-strip or type, and with lugs made to engage one another 95 for connecting the sections substantially as described.

6. A type-segment comprising sections each consisting of a hub portion, a rim portion and spokes, said rim being provided with 100 type-strip holders, and the outer spokes being provided with lugs for connecting the sections substantially as described.

7. A type-segment comprising sections provided with type-holders and with lugs for 105 connecting the sections, said sections being corrugated or flanged so as to stiffen the segment and to bring the lugs to engagement with one another substantially as described.

8. A type-segment comprising top and bottom sections each consisting of a hub portion, a rim portion and spokes, said sections being flanged and secured together at a suitable distance or space to receive a type-strip or type therebetween, and a sleeve or hub secured to the hub portions of the sections substantially as described. 110

9. A type-writing machine provided with a shiftable type-segment, a differentially-slotted base-plate, shift-levers for the segment 120 limited in their play by the base-plate, a plunger made to normally rest on the plate and adapted to be shifted by the levers, and an arm on the plunger made to engage the segment or its hub substantially as described. 125

10. A type-writing machine provided with a shiftable type-segment having a flanged hub, a differentially-slotted base-plate, shift-levers limited in play by the plate, and a plunger actuated by the levers and provided with an 130 arm made to engage the flange of the segment or hub substantially as described.

11. A type-writing machine provided with a shiftable type-segment, shift-levers, and a

plunger actuated by the levers and having a segment-engaging arm composed of two jointed sections one of the sections being normally in position to engage the segment and adapted 5 to be swung clear of the segment substantially as described.

12. A type-writing machine provided with two type or case shifting levers, and a two-armed lever having the ends of its arms inclined or cam-shaped to respectively engage 10 or lock the shift-levers substantially as described.

13. A type-writing machine provided with type or case shifting levers, and a lock-lever 15 common to and fulcrumed between the shift-levers substantially as described.

14. A type-writing machine provided with a fulcrum-block, shift-levers fulcrumed to sides of the block, and a lock-lever fulcrumed on 20 top of the block above the shift-levers so as to be common to the latter substantially as described.

15. A type-writing machine provided with a positioning-lever, a printing-lever fulcrumed 25 to the positioning-lever, and keys made to directly actuate or engage the printing-lever substantially as described.

16. A type-writing machine provided with a positioning-lever, a printing-lever fulcrumed 30 to the positioning-lever, and with keys, said printing-lever having its front portion made to directly engage or support the keys substantially as described.

17. A type-writing machine provided with a 35 positioning-lever, a printing-lever fulcrumed to and made to extend forward of the positioning-lever, and keys fulcrumed back of the front of the printing-lever and made to rest on or engage said front substantially as de- 40 scribed.

18. A type-writing machine provided with a positioning-lever, a transmission-lever connected directly or positively to the positioning-lever, a printing-lever and keys substan- 45 tially as described.

19. A type-writing machine provided with a rigid or non-yielding hammer, a printing-lever made to positively actuate the hammer, and keys for the printing-lever substantially 50 as described.

20. A type-writing machine provided with a positioning-lever, a printing-lever fulcrumed to the positioning-lever, a hammer engaged by the rear of the printing-lever, and keys

made to engage the front of the printing-le- 55 ver substantially as described.

21. A type-writing machine provided with a rigid or non-yielding hammer, a detent for the hammer, and a lever made to positively engage or actuate the hammer and detent 60 substantially as described.

22. A type writing machine provided with a rigid or non-yielding hammer, a detent for the hammer, and a lever made to positively 65 actuate the hammer and detent independently of one another substantially as described.

23. A type-writing machine provided with a carriage, a feed-dog, and a rock-shaft for actuating the feed-dog, said rock-shaft being extended from the front toward the rear of 70 the machine substantially as described.

24. A type-writing machine provided with a carriage, a feed-dog, keys, and a rock-shaft provided with laterally-extending arms, one of the arms being connected or linked to the 75 feed-dog and the other arm being engaged or actuated by the keys substantially as described.

25. A type-segment comprising sections for holding the type-strip or type, said sections 80 being provided with lugs for connecting the sections, said sections being corrugated or flanged so as to stiffen the segment and to bring the lugs to engagement with one another, substantially as described. 85

26. A type-segment, a shaft, a stop-arm for the segment mounted on the shaft, a lever for actuating the segment, a positive stop or key for arresting the stop-arm, a printing-lever, and a hammer positively or directly actuated 90 by the printing-lever substantially as described.

27. A type-segment, a shaft, a stop-arm for the segment mounted on the shaft, a lever for actuating the segment, keys for actuating 95 the segment-actuating lever and for positively or directly arresting the stop-arm, a printing-lever actuated by the keys, and a hammer positively or directly actuated by the printing-lever substantially as described. 100

In testimony whereof I have hereunto set my hand in the presence of two subscribing witnesses.

WILLIAM P. QUENTELL.
